REFRIGERANT COMPRESSOR

Willy Hirche, Leopoldshain, near Gorlitz,
GermanyApplication September 5, 1931, Serial No. 561,453
In Germany September 10, 1930

1 Claim. (Cl. 230—234)

This invention relates to a novel refrigerant compressor, in which objection is overcome in that the electric motor is situated in a gas-proof casing, which is removably fitted on the 5 compressor casing. The motor lies removably on the compressor shaft, the shaft bearings being all in the compressor casing which is packed at the point where the driving shaft passes, so that neither oil nor cooling medium can pass into 10 the casing or, if this is removed for the purpose of changing the motor in the event of damage, into the atmosphere, and air cannot penetrate into the compressor casing.

An embodiment of the invention is illustrated 15 diagrammatically in the only figure of the accompanying drawing.

The compressor 1 is here shown as an ordinary piston compressor with crank-shaft. It is evident, that a rotary piston compressor or the 20 like may be employed. Casing 2 is gas-tightly closed. The armature 1 of the motor is slipped onto the shaft 4 by means of a sleeve, so that it can easily be removed. The armature 1 and the stator winding 8 are accommodated in a 25 common compartment 12 of the casing 2. The casing 2 is gas tightly fitted at 9 on the compressor casing. The compressor wall 11 extends continuously from one end to the other, or is divided at the connecting point 9 with the motor 30 casing 2. The interior space 3 of the compressor receives the cooling medium or oil, or both. The compressor shaft 4 serves at the same time as armature shaft of the motor. The shaft 4 runs in bearings 5 and 6 arranged inside the compressor 35 casing. A suitably constructed shaft packing 10 is provided between the compressor and motor casings.

If, for any reasons, the electric motor has to 40 be removed, this can be effected in a simple manner, as the packing 10 does not permit of oil and cooling medium leaking from the compressor and protects the compressor against the penetration of air. There are also no bearings

on the motor which might cause trouble during its removal. The armature 1 can also be easily dismantled. In service, the advantage is derived that the motor remains free from oil and cooling medium and that, even in the case of 5 leakages of the shaft packing, no communication can take place between the compressor casing and the atmosphere, but in this instance small quantities of cooling medium may penetrate into the motor casing which however can- 10 not prove detrimental if the motor is suitably constructed. When employing SO_2 as cooling medium, the motor can be protected against the SO_2 by simple normal means.

The crank case 3 is packed against the atmosphere by the wall 11 having at its lower end an aperture closed by a removable plug 13. The inner space 12 of the motor casing is likewise packed against the atmosphere by the wall 2. The crank case 3 and the space 12 of the motor 20 casing are protected and separated by a wall which belongs either to the casing 2 or to the casing 11. At the point at which this gas-proof partition is mounted, through which the common shaft 4 extends, the shaft packing 10 is 25 arranged. This novel construction therefore possesses all the advantages of a gas-tightly closed refrigerant compressor and nevertheless allows the driving motor to be easily exchanged.

30

I claim:

A refrigerating compressor comprising in combination a compressor casing, a compressor shaft projecting from said compressor casing, a motor comprising a rotor and a stator, said rotor mounted directly on the projecting end of said shaft, a gas- and oil-tight motor casing surrounding said motor, carrying the stator of the motor and removably attached to said compressor casing, bearings for said shaft in said compressor casing, and a gas and oil-tight pack- 40 ing at the point where said shaft passes from said compressor casing into said motor casing.

WILLY HIRCHE.
